(57) **CLAIM**

The ornamental design for a housing for water monitoring device, as shown and described.

DESCRIPTION

FIG. 1 is a front side perspective view of a housing for a water monitoring device showing the claimed design; FIG. 2 is another front side perspective view thereof; FIG. 3 is a bottom front perspective view thereof; FIG. 4 a rear side perspective view thereof; FIG. 5 is a front view thereof; FIG. 6 is a rear view thereof; FIG. 7 is a side view thereof; FIG. 8 is another side view thereof; FIG. 9 is a top view thereof; and, FIG. 10 is a bottom view thereof.

The shade lines in the Figures show contour and not surface ornamentation.

The broken lines in the Figures show portions of the housing for water monitoring device and a conduit of indeterminate length, which form no part of the claimed design.
